VALANCE FOR MATTRESSES, CUSHIONS, PADS, AND THE LIKE

Filed April 5, 1928

UNITED STATES PATENT OFFICE

THOMAS M. COGHLAN, OF KANKAKEE, ILLINOIS

VALANCE FOR MATTRESSES, CUSHIONS, PADS, AND THE LIKE

Application filed April 5, 1928. Serial No. 267,588.

This invention relates to the upholstery art and has reference more particularly to valances for mattresses, pads and the like.

The principal object of the invention is the provision of a new and improved valance which is adapted to be attached to the edges of pads, cushions or mattresses for concealing the supporting springs and for enhancing the appearance of the structure.

10 Another object of the invention is the provision of a new and improved valance that is so constructed that when attached, it will hang in proper position from the mattress or pad.

15 A further object of the invention is the provision of a new and improved valance that may be manufactured as an attachment, that is simple in construction, cheap to manufacture, easily attached, neat in appearance, and 20 that may be employed on the conventional type of pads and mattresses.

Other and further objects and advantages of the invention will appear from the following description taken in connection with the 25 accompanying drawings in which

Fig. 1 is an elevation of a portion of the valance;

Fig. 2 is a section on line 2—2 of Fig. 1;

Fig. 3 is a section on line 3—3 of Fig. 1;

30 Fig. 4 is a side elevation of a portion of a mattress showing the invention in position thereon, with parts in section and parts broken away; and

Fig. 5 is a view similar to Fig. 4 showing 35 the invention applied to a pad.

In the use of the conventional pads, mattresses and the like, supporting springs are usually employed. These springs are more or less unsightly and the present invention 40 seeks to conceal the same by a valance that will have all the appearance of being in reality a portion of the mattress or pad. When employed on a pad, the pad will have the appearance of a box mattress and when employed on a mattress the structure will have the appearance of a box mattress of unusual thickness.

Referring now to the drawings, the reference character 10 designates the valance 50 which comprises the two fabrics 11 and 12

stitched together along their lower edges as at 13. The fabrics are stitched together transversely at intervals as at 14 to form pipes or compartments 15 which are adapted to contain filling 16 of any suitable material. 55

It is desirable that the valance when in position on the mattress shall not extend outwardly beyond a vertical plane. It may incline inwardly in which event it will grip the springs and prevent any tendency of the edge 60 portions of the mattress to turn or curl up along the side edges while the mattress is in use. It is desirable, however, that the valance should hang vertically from the mattress, pad or cushion in order not to detract 65 from the appearance of the construction.

It is well known, that a mattress or pad will become from two to four inches shorter in length and from one to two inches shorter in width on inserting the filling and tufting 70 the same, consequently if the valance be attached before the filling is inserted, the lower periphery of the valance will be several inches longer than the upper attached edge after the mattress is completed due to the fact that the upper edge being attached to the bed or roll of the tufted mattress will follow the contour of the tufted portion as shown at 30 in Fig. 4. In order that the valance shall hang substantially vertical 75 under these circumstances, the fabrics of the valance are shortened at their lower edges to compensate for this shortening of the upper edge as by removing a triangular portion in the lower edge portions of the inner and outer fabrics 11 and 12 or by forming triangular plaits or folds 17 therein, as indicated in Figs. 1, 2 and 4. In order that the material shall not be drawn laterally, a 80 number of these plaits are employed. In order that the material may be taken up evenly so as not to draw the fabrics, these plaits are arranged a few inches apart throughout the full length of the valance. 85

The valance may be cut to the desired 90 lengths, filled, the lower edges shortened, and the ends sewed together ready to be attached to the edges of the pad, cushion, or mattress as required. Or, after being prepared, the valance may be manufactured in strips, 100

filled, and rolled or folded in packages ready for use. It may then be cut to the proper length as needed, and attached to the cushion or pad as a separate attachment, the ends being connected together by stitching in the usual manner.

In Fig. 4, the valance is shown as being attached to a box mattress 18 of the usual construction, while in Fig. 5, the valance is shown as being attached to a pad 19 of the conventional type. In the former construction, the structure will have the appearance of a conventional mattress. In both cases, the supporting spring assembly 20 will be effectively concealed by the valance.

While I have shown the valance as being attached to the lower peripheral edge of the mattress and to the seam of the pad, it is understood it may be attached to these members in any suitable manner and with any suitable means.

I claim as my invention:

1. In combination, a pad, a valance comprising a long padded fabric member secured to the edge of said pad and depending therefrom, said valance having triangular plaits in the inner and outer fabrics of said pad, the lower edge of said valance being unattached.

2. In combination, a mattress, a spring assembly for supporting said mattress, a padded valance secured to said mattress and extending alongside said spring assembly for concealing the same, said valance having triangular plaits in its outer containing fabric at intervals along each side for causing said valance to grip said spring assembly, the edge of said valance farthest removed from said mattress being free.

40 In testimony whereof I affix my signature.
THOMAS M. COGHLAN.
